UNITED STATES PATENT OFFICE.

GEORGE F. ROSE, OF HYNDSVILLE, NEW YORK.

TYPEWRITER CONSTRUCTION.

Application filed December 19, 1921. Serial No. 523,317.

To all whom it may concern:

Be it known that I, GEORGE F. ROSE, of Hyndsville, in the county of Schoharie and State of New York, a citizen of the United States, have invented certain new and useful Improvements in Typewriter Construction; and I do hereby declare the following to be a full, clear, and exact description of the same, reference being had to the accompanying drawings, forming a part of this specification, and to the reference numerals marked thereon.

This invention relates to typewriting machines and more especially to the striking type bar variety, the chief object being to provide an efficient supporting means for the type bars affording precision in the location and movement of the latter, which means may be readily stamped up from sheet metal and which is therefore economical in material and in cost of manufacture. To these and other ends the invention resides in certain improvements and combinations of parts all as will hereinafter be more fully described, the novel features being pointed out in the claims at the end of the specification.

In the drawings:

Figure 1 is a side elevation of a typewriting machine embodying the present invention, with parts broken away and in section;

Figure 2 is an enlarged front elevation of the type bar supporting means detached;

Figure 3 is a section on the line 3^a—3^a of Figure 2;

Figure 4 is a section on the line 4^a—4^a of Figure 3; and

Figure 5 is a section on the line 5^a—5^a of Figure 3;

Similar reference numerals throughout the several views indicate the same parts.

The invention is embodied in the present instance, by way of illustration, in conjunction with a well known variety of typewriting machine comprising a main frame indicated generally at 10, on the rear portion of which is supported a traveling work carriage 11 provided with a roller platen 12. At 13 is indicated ribbon supporting and feeding mechanism. Key levers are indicated at 14, arranged in banks and supported on a suitable bridge 15 carried by the main frame. The rear ends of the key levers are connected by actuating link means 16 with type bars shown at 17 which are pivotally supported on the main frame for striking

movement toward and from the platen, in which movement they engage and operate carriage spacing mechanism.

The present improvement resides in means for movably supporting and guiding type bars 17 on the main frame. As well understood in the art, the bars require support by means insuring not only the accurate positioning of the same but also precise guiding of the movements of the bars so that all of the type will strike accurately in the printing position. While the type bars must be precisely guided in their movements, as stated, this must be accomplished without undue frictional resistance, to which end it is desirable that the supporting means be so constructed as to facilitate accurate finishing of the guiding surfaces and to maintain the latter rigidly in their proper relative relations.

It has been found that these ends may be accomplished in an improved manner by forming up the type bar supporting means from sheet metal and mounting the same on a wall or plate member 18 extending transversely of the main frame and preferably located and inclined for the purposes set forth in my said co-pending application Serial No. 521,227, filed December 9, 1921, for typewriters. The type bar supporting means proper comprises a one piece sheet metal sector or member indicated generally at 19 formed from a plate of arcuate shape as indicated in Figure 2, which is stamped up and formed as hereafter described to provide bearings for the type bars and is secured on the transverse support 18 of the frame, in the position indicated in Figure 1, as by means of screws or rivets 20.

Plate 19 preferably has its longitudinally extending central portion stamped up as best shown in Figures 4 and 5 to provide a projection or rib 21 of substantially U-shape at one or both sides of which the metal is formed to provide stiffening angles or offsets 22 and flanges 23. The flanges in the present instance are perforated as at 24 for the reception of the screws or rivets securing the same to the frame support 18.

The bearing for the type bars is formed by drawing the metal adjacent the center of rib 21 inwardly, or in a reentrant direction as at 25, so as to provide a recess 26 extending longitudinally from end to end of the supporting plate and thus transversely of the machine. In the bearing portion thus

formed in rib 21 is carried a pintle means or rod 27 inserted therein from one end and held in place by means of several keeper portions 28 of the plate drawn inwardly to a 5 less distance than the bearing portion, as shown, and located at intervals from end to end of the plate.

The rib portion 21 of the supporting plate has a series of guide slots cut therein extending 10 radially from the printing point, for the reception of the respective type bars which are supported and guided in these slots. The latter are not carried deep enough, however, to cut into the offsets 22 and flanges 23; 15 it being important for purposes of stiffness to maintain these intact. The slots are cut after the plate is stamped up as described and are preferably subsequently milled or finished to the precise dimensions desired to 20 provide an accurate guiding fit with the type bars. The latter have their rear ends of substantially circular shape as indicated at 30 with a concentric opening through which the pintle means or rod 27 is passed after 25 the type bars are located in their respective guide slots 29.

The above described type bar support embodies a substantially one piece construction 30 which can be stamped up from sheet metal and assembled economically with respect to cost of labor as well as materials, and affords the advantage of a light weight which is particularly important in machines of a portable type. It is evident from the form 35 of the arcuate plate shown and described that the supporting means is not only rigid in character but permits of the accurate milling or finishing of the bar receiving slots 29, and also of the bearing recess 26, if necessary, in fixed relation to each other, so as to insure precise positioning of the levers and precise guiding of their movements.

I claim as my invention:

1. In a typewriting machine, the combination with a frame and a plurality of type bars, of a one-piece, sheet metal member on 45 the frame having a portion thereof stamped up angularly to form guide means and a second portion in substantially spaced relation with said first portion stamped up to form a bearing for pivot means, with spaced guide slots cut through said guide means and bearing for the reception of said type bars, and means pivotally supporting said bars on said bearing portion.

2. In a typewriting machine, the combination with a frame and a plurality of type bars, of a one piece sheet metal member carried by the frame having a longitudinally extending portion thereof stamped up to form a projecting rib with the metal of a portion of the latter drawn inwardly to 60 form a bearing, said rib being cut by a plurality of guide slots for the reception of the type bars, and means on said type bars

pivots supporting the same on said bearing in their respective guide slots.

3. In a typewriting machine, the combination with a frame and a plurality of type bars, of a one piece sheet metal member carried by the frame having its longitudinally extending central portion stamped up in substantially U-shape with a reentrant portion forming a bearing, said U-shaped portion being cut by a plurality of guide slots for the reception of the type bars, and means on the latter pivotally supporting the same on said bearing portion. 70

4. In a typewriting machine, the combination with a frame and a plurality of type bars, of a one piece sheet metal member carried by the frame having a longitudinally extending portion thereof stamped up to form a projecting rib with the metal of a portion of the latter drawn inwardly at different distances to form a bearing and keeper means therefor, said rib having guide slots cut therethrough for the reception of the type bars, and pintle means inserted in said bearing beneath said keeper means for 80 pivotally supporting the type bars. 85

5. In a typewriting machine, the combination with a frame having a transversely extending support and a plurality of type bars, of a one piece sheet metal member extending transversely of the frame with flanges at its sides secured to said support and with a central portion between said flanges stamped up to form a rib having a bearing portion therein, said rib having 95 guide slots cut therethrough for the reception of said type bars and pintle means carried in said bearing portion for pivotally supporting said type bars. 100

6. In a typewriting machine, the combination with a frame and a plurality of type bars, of a one piece sheet metal member carried by the frame having a longitudinally extending portion thereof stamped up to form a projecting rib provided with a bearing and having also stiffening offsets and flanges at the sides of said rib with said flanges secured to the frame, said rib having 110 guide slots cut therein for the reception of said type bars, and means pivotally supporting said bars on said bearing. 115

7. In a typewriting machine, the combination with a frame and a plurality of type bars, of an arcuate sheet metal strip on said frame having a longitudinally extending, central portion thereof stamped up to form a bearing for pintle means and having a second portion in parallel spaced relation with the first portion stamped up in a direction transverse to said bearing to form 120 guide means, with spaced slots cut transversely of said bearing through the latter and said guide means for the reception of said type bars, and pintle means supporting said bars on said bearing portion. 125

8. In a typewriting machine, the combination with a frame and a plurality of type bars, of an arc-shaped sheet metal plate on the frame stamped up from a single piece 5 of material to provide a rib having a portion thereof formed to afford a bearing and a stiffening offset, said rib and bearing portion having guide slots cut transversely therethrough for the reception of the type 10 bars, and pintle means for pivotally supporting said type bars on said bearing portion.
9. In a typewriting machine, the combination with a frame and a plurality of type 15 bars, of an arc-shaped sheet metal plate on the frame stamped up in substantially U-shape with a reentrant portion forming a bearing, said U-shaped portion having a plurality of slots cut transversely there- through for the reception of said type bars, 20 and means on the latter pivotally supporting the same on said bearing portion.
10. In a typewriting machine, the combination with a frame having a transversely extending support and a plurality of type 25 bars of an arc-shaped sheet metal plate extending transversely of the frame and stamped up to form a rib portion with stiffening offsets and side flanges secured to said support and with a portion of said rib 30 portion drawn inwardly to form a bearing, said rib portion having guide slots cut therethrough for the reception of said type bars, and arc-shaped pintle means in said bearing pivotally supporting said type bars in their 35 respective slots.

GEORGE F. ROSE.
